HOISTING MECHANISM

Filed May 1, 1924

UNITED STATES PATENT OFFICE

CHARLES F. OSGOOD, OF CLAREMONT, NEW HAMPSHIRE, ASSIGNOR TO SULLIVAN MANUFACTURING COMPANY, A CORPORATION OF MASSACHUSETTS

HOISTING MECHANISM

Application filed May 1, 1924. Serial No. 710,324.

This invention relates to hoisting mechanisms.

It has for its object to provide an improved hoisting mechanism. A further object is to provide improved control means therefor.

5 Another object is to provide an improved double drum hoist with improved means for alternatively connecting the drums to a driving motor. Another object is to provide in combination with a drum and driving motor therefor, improved means for connecting the drum in driving relation to the driving motor, which means constitutes manually operable means adapted to simultaneously control both 10 elements.

15 In the accompanying drawings I have shown for purposes of illustration three forms which my invention may assume in practice.

20 In these drawings,—

Fig. 1 is a side elevation partly broken away to show details of construction.

Fig. 2 is an end elevation partly broken away to show details of construction.

25 Fig. 3 is a sectional view of the control valve.

Fig. 4 is a modified form of control valve.

Fig. 5 is an end elevation of a modified form of hoisting mechanism.

30 In the illustrative embodiments of my invention, I have shown the same applied to a double drum hoist, although it will be obvious that the same is applicable to a single drum hoist also. More specifically, 35 the same comprises a base 1 having standards 2 and 3 projecting upwardly from the opposite ends thereof, and a central stationary motor 4 disposed between the drums 5 and 6 which are rotatably supported by the motor 40 casing and standards. This form of hoisting mechanism is well known, and further details, briefly described, comprises a frictionally controlled internal gear 7 adapted to be held or allowed to freely rotate in a bearing 8 mounted within the standard 3. Inasmuch as the structure for each drum is identical, description of one end will suffice for both. The gear 7 is held by a friction band 9 controlled by a suitable mechanism hereinafter described, and when the same is so held, power

will flow from the motor through suitable reduction gearing 10 to drive the drum. The gearing 10 is carried by a head 11 formed on the outer end of the drum, this head having a stub shaft 12 also rotatably mounted within the hub of gear 7.

Improved automatic means are herein provided for controlling the operation of the friction bands so that the same is dependent upon the operation of the motor. This

means comprises a cylinder 13 disposed within the frame 1 and transversely of the drum axis. A piston 14 reciprocably mounted therein has a piston rod 15 connected as by a pin and slot connection to a bell crank 16

55 pivotally mounted on an arm 17 carried at the forward side of the frame 1. The ends of the friction band 9 are connected to the bell crank as at 18 and 19 and so arranged that when the piston 14 is forced outwardly, the

50 friction band 9 will hold the internal gear 7, thereby acting as a clutch mechanism for controlling rotation of the drum. A cylinder is provided for each of the internal gears 7, but it will of course be understood that if

55 desired, one cylinder and piston could be used for controlling the same inasmuch as they are alternatively operated.

60 In the preferred form of my invention, I have shown an air type motor, the actuating fluid for which is controlled by a valve 20 having an inlet 22 and outlet 21, the latter provided with suitable piping to deliver such actuating fluid to the motor. Communi-

65 cation between the pipes 21 and 22 is had by way of a peripheral passage 23 formed in the valve part 24 rotatably mounted within a bore 25. In the position of the valve shown in Fig. 3, the passage 23 will also

70 allow flow of fluid through a pipe 26, while a second pipe 27 diametrically opposed thereto is vented to the atmosphere by a passage 28. In order to obtain the dependent opera-

75 tion between the motor and the respective drums, the pipes 26 and 27 will be connected to the cylinders 13 for controlling the friction bands of the respective drums.

80 In the operation, it will be seen that when the valve is in the position shown in Fig. 3, fluid will flow to the motor and through the

100

pipe 26 to actuate the piston 14 for the right hand friction band to hold the corresponding internal gear stationary and cause rotation of the drum 5. At the same time the cylinder for the left hand drum will be vented to the atmosphere as by the vent passage 28, thus allowing the left hand internal gear to be freely rotated; and consequently the drum 6 will not be driven. By turning the valve part 24 180°, it will be seen that the pipe 27 will be placed in communication with the inlet pipe 22 and thereby allow the flow of pressure fluid to the left hand cylinder 13, to cause operation of drum 6 while drum 5 is now free.

In Fig. 4 I have shown a modified form of the control valve comprising a casing 29 with a usual rotatable central member 30 having a central live pressure fluid inlet passage 31 adapted to communicate with the passage 21 leading to the motor as by a peripheral groove 32. When the member 30 is in the position shown in Fig. 4, the passage 26 leading to the cylinder for actuating the right hand friction control band will be in communication with the source of live pressure fluid through the passage 31, while the passage 27 leading to the cylinder for the left hand drum will be vented to the atmosphere as by a passage 33 and a peripheral groove 34. When the valve is turned 90 degrees from its present position, live fluid will continuously flow to the motor but the passage 26 will be brought into communication with the passage 33 as by the groove 34 thus releasing the right hand drum and allowing flow of live pressure fluid from the passage 31 to the cylinder for the left hand drum as through the peripheral groove 32 and passage 27.

In the modified form shown in Fig. 5, the motive power comprises an electric motor and a suitable switch is used whereby when thrown in one direction, current will flow to energize a solenoid 35 corresponding to one of the cylinders 13. A usual plunger 36 cooperates with the solenoid to actuate the friction bands as in the first case. When the switch is thrown in the opposite direction, a second solenoid which is provided for the other friction band will of course be actuated.

While I have in this application specifically described three forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A haulage mechanism comprising a motor, a plurality of winding drums rotatable independently of said motor, driving con-

nections between the motor and said drums operative to effect rotation in the same direction of each drum without reversal of the motor, said driving connections comprising power transmission connections with the motor individual to each drum and each comprising means for selectively rendering it effective or interrupting power transmission thereby to its respective drum, controlling mechanism individual to each of said last mentioned means operative on supply of actuating medium thereto to actuate its controlled means to effect drum drive, and means for controlling said motor and said controlling mechanisms operative to supply actuating medium to the motor, and to one or another of said controlling mechanisms separately only when actuating medium is flowing to the motor, and having a single controlling member movable to different positions to effect control of said different controlling mechanisms.

2. In a haulage mechanism, a motor operative on supply of motive medium thereto, a plurality of rotatable winding drums, means associated with each drum for transmitting power from said motor thereto separately to cause driving thereof, said means each including power transmission controlling devices controllable either to effect transmission of rotation from the motor to its respective drum or to release the drum from driving connection with the motor thereby to permit free rotation thereof, operating mechanisms for said power transmission controlling devices operable by the same kind of motive medium as said motor, and controlling means for said motor and for said operating mechanisms including an operator controlled element movable to different positions to effect the rotation of different drums and controlling means governed by said operating element and in each of said positions of the latter effecting motive medium supply to the motor and to one power transmission controlling device operating mechanism.

3. In a haulage mechanism, a motor operative on supply of motive medium thereto, a plurality of rotatable winding drums, means associated with each drum for transmitting power from said motor thereto separately to cause driving thereof, said means each including power transmission controlling devices controllable either to effect transmission of rotation from the motor to its respective drum or to release the drum from driving connection with the motor, thereby to permit free rotation thereof, operating mechanisms for said power transmission controlling devices operable by the same kind of motive medium as said motor, and a common controlling mechanism for said motor and for said operating mechanisms including a control element movable to different positions in each of which it effects motive medium supply to the

- motor and in one of which it effects motive medium supply to one power transmission controlling device operating mechanism and in another of which it effects motive medium supply to another power transmission controlling device operating mechanism. 5 means, said common control means controlling the supply of actuating medium to said driving connections control means and movable to different positions to determine the one to be supplied only when actuating medium is flowing to the motor. 70
4. In a haulage mechanism, a motor operative on supply of motive medium thereto, a plurality of rotatable winding drums, means associated with each drum for transmitting power from said motor thereto separately to cause driving thereof, said means each including power transmission controlling devices controllable either to effect transmission of rotation from the motor to its respective drum or to release the drum from driving connection with the motor, thereby to permit free rotation thereof, operating mechanisms for said power transmission controlling devices operable by the same kind of motive medium as said motor, and a common controlling mechanism for said motor and for said operating mechanisms including a member adapted to be placed in and between different positions in one of which it effects motive medium supply to one of said power transmission controlling device operating mechanisms and in the other of which it effects motive medium supply to the other of said power transmission controlling device operating mechanisms, and in both of which, and also in intermediate positions, it effects supply of motive medium to said motor. 10 15 20 25 30 35 40 45 50 55 60 65 70 75 80 85 90 95 100 105 110 115 120 125 130
5. A haulage mechanism comprising a motor, a plurality of independently rotatable winding drums, means provided for each drum adapted to constitute driving connections between the respective drum and the motor, said means each including a frictionally controlled reaction member, means for controlling flow of energy medium to said motor, and means controlled by said motor control means for selectively actuating said friction controls for said reaction members to effect driving of one or another of said drums, said motor and said actuating means for said friction controls being supplied from a common source with actuating medium, said actuating means for said friction controls being connected to be energized only when energy medium is flowing to the motor. 10 15 20 25 30 35 40 45 50 55 60 65 70 75 80 85 90 95 100 105 110 115 120 125 130
6. A haulage mechanism comprising a motor, a plurality of independently rotatable winding drums, means for effecting drive of each drum without motor reversal including means individual to each drum adapted to constitute driving connections between the respective drum and the motor during rotation of the latter in the same direction, driving connections control means for bringing one of said driving connections into operation at a time when supplied with power medium, and common control means for the supplies of actuating medium to the motor and to said driving connections control means, said common control means controlling the supply of actuating medium to said driving connections control means and movable to different positions to determine the one to be supplied only when actuating medium is flowing to the motor. 70
7. In a hoist, a fluid actuated motor, a pair of relatively rotatable winding drums, driving connections between said motor and each of said drums, fluid actuated drive control means for each of said driving connections, and a common valve for controlling fluid flow to said motor and selectively to each of said drive control means. 75
8. In a hoist, a fluid actuated motor, a pair of relatively rotatable winding drums, driving connections between said motor and each of said drums, fluid actuated drive control means for each of said driving connections, and a common valve for controlling fluid flow to said motor and selectively to each of said drive control means, said valve having provision for connecting the source of fluid with but one drive control means at a time. 80
9. In a hoist, a unidirectional motor, a pair of relatively rotatable winding drums, driving connections between said motor and said drums permitting independent driving of the latter, controlling means for said motor, and control means for said driving connections for permitting selective drive of either drum alone directly controlled by said motor control means, said motor controlling means having one operative position in which but one of said drums may be driven and another operative position in which only the other of said drums may be driven. 90
10. In a hoist, a fluid pressure operated motor, a pair of relatively rotatable winding drums, driving mechanism for said drums driven by said motor, and fluid pressure actuated controlling means for said driving mechanism including means forming a plurality of expansible chambers into which pressure fluid may be selectively supplied to effect drive of different drums, said drive control means being supplied with operating medium from a common source with said motor, and a single manually operable member for controlling the supply of actuating medium to said motor and to said expansible chambers, said manually operable member being movable to direct actuating medium to either of said expansible chamber selectively. 105 110
11. In a hoist, a motor, a pair of relatively rotatable winding drums, driving connections between said motor and said drums permitting independent driving of the latter, controlling means for said motor including a movable member, and controlling means for said driving connections for permitting selective drive of either drum alone, said latter controlling means being directly connected to said movable member so as to be directly controlled thereby. 120 125 130

12. In a hoist, a motor, a pair of relatively rotatable winding drums, driving connections between said motor and said drums for selectively connecting the latter independently of each other for driving by said motor, controlling means for the motor, and means controlled by the motor controlling means and actuated independently of the motion of the motor for controlling said driving connections to effect selectively independent drive of one drum or of the other in accordance with the particular operation of said motor controlling means.

In testimony whereof I affix my signature.
CHARLES F. OSGOOD.
